UNITED STATES PATENT OFFICE.

FRED W. GESALMAN, OF GREENSBURG, PENNSYLVANIA, ASSIGNOR TO PENNSYLVANIA RUBBER COMPANY, OF JEANNETTE, PENNSYLVANIA, A CORPORATION OF PENNSYLVANIA.

TENNIS-BALL-COVERING MACHINE.

Application filed March 29, 1928. Serial No. 265,749.

This invention relates to improvements in apparatus for covering balls with pliant sheet material, and, though not limited to balls of particular material or size or character, it finds application in the covering of rubber tennis balls with fabric, and in that application I shall show and describe it.

In the accompanying drawings Fig. I is a view in plan; Fig. II, a view in front elevation; and Fig. III, a view in side elevation of a machine embodying my invention.

Two cups 1 are mounted in axial alignment in a suitable frame. One at least of these two cups is axially movable, and the proportions are such that on recession the pair of cups will receive between them the rubber ball to be covered, and will then advance to engage at opposite poles a ball in place between them. The cups make their engagement yieldingly upon the ball, and a convenient and adequate arrangement is that shown. The two cups 1 are mounted on rotatable shafts 2 and 3. These shafts are in this instance, both of them, axially movable in their bearings, and movement is controlled by a weighted hand lever 4. The lever, fulcrumed at an interval from the point of engagement, engages by its bifurcated work arm a block 5 upon shaft 3. This block and a corresponding block 6 on shaft 2 are linked to a vertically moving slide 7, to the end that the swinging of lever 4 effects simultaneous and opposite reciprocation of the two cups 1. It will be perceived that an attendant may swing the hand lever, to cause the space at which the cups stand apart to widen, and, that when the attendant releases the lever, the weight may be adequate to cause the cups to close upon a ball introduced between them and to hold the ball in place. The yielding pressure under which the ball is secured will not be so great as appreciably to crush and distort the ball, and it will be great enough to cause the engaged ball (and through the ball, shaft 2 also) to rotate, when shaft 3 rotates, with sufficient force to overcome the resistance due to engagement with the cover material in the manner to be described. It

will be observed of the ball engaging and driving means that, engaging the ball oppositely at opposite polar regions, they leave the surface of the ball free over a medial equatorial region.

Adjacently placed is a movable platform or support, here shown as a block 9, engaged by suitable guides in the frame of the machine. This block is so situated that its face extends in a plane substantially tangent to a ball in place between the cups, and in its movement the face of the block reciprocates in that plane. The face of the block is adapted to receive and carry a sheet of cover material.

The block 9 is reciprocated by hand in its guide way in left to right direction, as seen in Fig. III, and to such end it is equipped with a handle 16. Means are provided for causing shaft 3, and with shaft 3 a supported ball and shaft 2 also, to rotate simultaneously and at coordinated speed, with the advance of block 9 from the position shown in Fig. III in left to right direction. The block 9 is provided with a rack 10 and a pinion 11 meshes with the rack. Pinion 11 is borne on a shaft 12, and from shaft 12 a gear train 13, 14, 15, 8 leads to shaft 3. Gear wheel 8 is borne on shaft 3. The arrangement and proportions are such as to achieve that coordination of movement just defined: when block 9 advances, a ball borne by and between cups 1, 1 rotates (in counter-clockwise direction, Fig. III) at an equatorial speed equal to the speed of advance of block 9.

At the beginning of operation a sheet of material resting on the block 9 is at its forward end at or near tangency to a ball in place between the cups. The range of block reciprocation is through an interval as great as the arc of ball curvature to be covered. In operation of the machine the ball is carried through a sufficient fraction of a complete rotation, and engagement of the ball with the cover material causes the ball to pick the material up, so that in one complete reciprocation the machine wraps the material accurately and evenly upon an equator of the ball.

A tennis ball is covered with two pieces of heavy fabric, ordinarily called felt. The two pieces are approximately of equal shape and size. They are of the familiar double-headed, figure-8 shape, and are applied on two great circles, perpendicular the one to the other, the ends of one piece meeting the other piece at opposite points of its waist or narrowest part. These pieces of fabric

are, preparatory to application, coated on one side with cement. In the operation of my machine a piece of fabric is accurately placed on the block, cement face up, and then, the prepared rubber ball being in position between the cups, operation of the machine wraps the piece accurately on a great circle around the ball. The shaping of the wrapped-on piece laterally to the spherical contour of the ball may be done by hand, and the application of the second and complementary piece of cover material may also be made by hand. The machine effects the accurate and rapid placement of the first piece.

I claim as my invention:

1. In apparatus for applying a cover to a ball, ball-supporting means adapted to engage the ball adjacent opposite poles, means for supporting a piece of pliant cover material, and means for simultaneously advancing the cover-supporting means and for rotating the ball-supporting means.

2. In apparatus for applying a cover to

a ball, a pair of oppositely borne, relatively and oppositely movable, and rotatable cups, means for yieldingly maintaining said cups in proximate position, a reciprocable cover carrier, and means for simultaneously reciprocating said carrier and rotating one of said cups.

3. In apparatus for applying a cover to a ball, means for supporting a ball and for rotating the supported ball on a diameter, a reciprocable slide provided with a cover-carrying face extending throughout the range of reciprocation in a constant plane, tangent to a supported ball, and means coordinated with the slide for driving the ball-rotating means.

4. The apparatus of claim 3, the coordination of means being such that the ball rotates at an equatorial speed equal to that of the cover-carrying slide.

In testimony whereof I have hereunto set my hand.

FRED W. GESALMAN.
